REFRIGERATING APPARATUS

Melvin S. Groh, Preston, Ontario, Canada

Application February 3, 1945, Serial No. 576,005
In Canada April 17, 1944

3 Claims. (Cl. 62—89)

1

The invention relates to improvements in refrigerating apparatus and more particularly to refrigerating apparatus which may be used in connection with ordinary frozen storage cabinets and the like.

It is an object of the invention to provide refrigerating apparatus in which one or more chambers may be maintained above the general temperature of the freezing chamber.

It is also an object of the invention to provide refrigerating apparatus in which one or more chambers having simple closures will maintain their contents cool without becoming frozen.

It is a further object of the invention to furnish refrigerating apparatus having easily accessible chambers therein which may be easily maintained at different variable temperatures.

With these and other objects in view the invention generally includes a freezing or cooling chamber having a plurality of closures in conjunction with which smaller cooled chambers having an insulated portion and a non-insulated portion are mounted. The smaller cooled chambers are designed to be detachably mountable in any one or all of the closure apertures and their number can be varied as storage requirements demand.

In the prior art, the structures generally employed are of two types, the first comprising a freezing chamber or plurality of such chambers adapted to be maintained at a more or less fixed temperature at or below freezing point, and a second type wherein more than one temperature is used. In practice these structures have certain defects since in the first type it is not always convenient to have the contents of the chambers become frozen and the extensive complication of parts necessitated in the second type renders them expensive and difficult to operate without giving any control over intermediate ranges of temperature. The instant invention, on the other hand, enables structures of either of these types to be used while permitting certain chambers to be held at variable temperatures which maintain their contents in a cool condition, without freezing.

These and other defects are overcome by the present invention in which:

Figure 1 is a perspective view of a refrigerating cabinet partially sectioned and showing a cooled chamber mounted on one of the apertures of the freezing chamber.

Figure 2 is a vertical sectional view through the cooling chamber and a cooled chamber.

Figure 3 is a vertical sectional view through

2

the cooling chamber and a cooled chamber showing the spacing means.

By referring to the drawings it will be seen that the freezing or cooling chamber 10, which is cooled by any suitable means such as the refrigerant coils 10a which are supplied with refrigerant from a suitable condensing unit (not shown), has the usual closures 11 and 12 in its upper surface 13. In the drawings the third closure means has been removed from the aperture 14 in the top surface 13 and on to the aperture the cooled chamber 15 is mounted. Cooled chambers 15 could, however, be mounted in any or all of the apertures.

By reference to Figure 2 it will be seen that the cooled chamber generally comprises the inner liner 16 made of any suitable good heat-conducting material and having the upper closure member 17 therein. It will be observed that the external upper portion and the lower internal portion of the heat-conducting liner 16 are insulated as indicated by the numerals 18 and 18a, the external insulation having the lower shoulders 19 and 20 which are adapted to be seated upon the corresponding rectangular rabbet 21 formed in the upper surface 13 of the freezing chamber. The lower portion 22 of the heat-conducting liner 16 thus is in heat exchange relation with the interior of the freezing or cooling cabinet.

The spacing of the cooled chamber 15 from the freezing or cooling chamber 10 may be effected by the spacing member represented in Figure 3 by the numeral 23, and made of non-conducting material shaped to fit the rabbet 21.

In operation the cooled chamber 15 is mounted as indicated in Figure 1, and it will be evident that the temperature within the insulated portion of the liner 16 will depend upon the amount of exteriorly uninsulated portion 22 which is in heat exchange relation with the freezing chamber 10, and since this may be controlled by the insertion of spacers 23, it is easy to control the temperature therein throughout at a point above that of the freezing chamber. A further means of controlling the temperature inside the liner is provided by the thickness of the insulation 18 and 18a, and thus variations in the extent and thickness of the inner and outer insulation of the liner, combined with variations in the depth to which the liner extends inside the freezing chamber may be used to compensate for changes in atmospheric conditions as between hot summer and normal weather conditions.

It is also apparent that in referring above to

the means of controlling the temperature inside the cooled chamber or inside the liner, the resultant of these means is that not only is the specific general temperature within the chamber under control but also the uniformity throughout the chamber is secured since it will be apparent that by insulating the lower inner portion of the chamber the cold temperatures of the cooling chamber are transmitted to the inner cooled chamber generally only by means of the outer 10 insulated liner so that conditions whereby the lower interior space within the cooled chamber is excessively cooled, while the upper interior portions are cooled simultaneously at a relatively higher temperature, are effectually prevented by these means.

It will be apparent that modifications may be made to the preferred structure as described, such changes being included within the scope and nature of the invention in accordance with the 20 herein appended claims.

What I claim as my invention is:

1. A removably mountable storage attachment for a refrigerator comprising, a liner fabricated from a heat conducting material to form a cooled chamber, heat insulation on the upper portion of said liner, the edge of said insulation forming an external shoulder on said cooled chamber, said cooled chamber having an opening in its top to admit articles to be stored and closure means therefor, the portion of said cooled chamber below said external shoulder being adapted to project through an aperture in the cooling chamber of a refrigerator to cause it to be disposed in heat exchange relation with the interior thereof, means for controlling the heat exchange between said cooled chamber and the cooling chamber of the refrigerator, said external shoulder formed by said insulation being adapted to engage with the 25 30 35

periphery of the aperture in said refrigerator cooled chamber to maintain said cooled chamber in heat exchange relation as aforesaid.

2. An attachment for a refrigerator as claimed in claim 1 in which said means for controlling the heat exchange between said cooled chamber and the cooling chamber of a refrigerator includes a predetermined amount of heat insulation on the lower portion of the interior surfaces of said liner.

3. An attachment for a refrigerator as claimed in claim 1 in which said means for controlling the heat exchange relation between said cooled chamber and the cooling chamber of a refrigerator includes spacers adapted to sit between said shoulder formed by said exterior insulation on said liner and the periphery of the aperture through which the lower portion of said liner is adapted to project, said spacers being adapted to vary the extent to which the lower portion of said liner projects into the cooling chamber of the refrigerator on which the attachment is mounted.
